HYDRAULIC JACK FOR SHOE MACHINES

Frank R. Thresh, Beverly, Mass., assignor to
United Shoe Machinery Corporation, Flemington, N. J., a corporation of New Jersey

Application June 24, 1948, Serial No. 34,903

25 Claims. (Cl. 1—41)

1

This invention relates to shoe machines having fluid pressure operated jacks adapted to support shoes thereon and to locate such shoes in operative position with relation to the instrumentalities of the machine which are to operate upon the shoes. By way of example, the invention is illustrated as embodied in a fastening inserting machine of the type disclosed in United States Letters Patent 1,849,253, issued March 15, 1932, on an application filed in the name of Fred N. LaChapelle, it being understood that the invention is limited neither in scope nor in utility to embodiment in a machine of that type but that it may be used to equally good advantage in any machine in which the work is supported on a jack and presented in operative relation to the machine by the jack.

It is the general purpose of the invention to improve upon and facilitate the operation of the jack and more specifically to provide improved fluid pressure operated jack mechanism by means of which the jack will be moved into its operative position by a preliminary pressure which should be sufficient to clamp the work against the customary work abutment but should at the same time still permit adjustments of the work with relation to the work abutment. Increased fluid pressure thereafter will establish the final operative position of the work and at the same time initiate the power operation of the machine.

To this end and in accordance with an important feature of the invention, the illustrated fastening inserting machine is provided with fluid-pressure actuated jack-operating mechanism including a fluid pressure circuit with which are connected a low pressure regulator and a high pressure regulator, an operator-controlled valve adapted to connect the circuit with a jack-elevating ram, additional means being associated with the valve for cutting off the low pressure regulator from the circuit after the elevation of the jack, thereby increasing the pressure of the fluid in the circuit and thus increasing the pressure of the jacked work against the work abutment.

In accordance with another feature of the invention, novel fluid-pressure operated clutch-tripping mechanism is provided, which mechanism is connectable to the above-mentioned fluid pressure circuit. The arrangement is such that that mechanism is maintained in its inoperative position until the pressure of the fluid in the circuit increases to a predetermined value, whereupon the mechanism is rendered operative to trip the clutch and to initiate the power operation of the machine.

2

These and other features of the invention will now be described in detail in connection with the accompanying drawings and will be pointed out in the appended claims.

5 In the drawings,

Fig. 1 is a view in right-hand side elevation of a fastening inserting machine in which the invention is embodied;

Fig. 2 is a section along the line II—III of Fig. 1;

Fig. 3 is a plan view of a valve mechanism associated with the jack-elevating mechanism;

Fig. 4 is a section along the line IV—IV of Fig. 3;

Fig. 5 is a section along the line V—V of Fig. 3;

Fig. 6 is a detail view of part of a treadle-controlled valve-operating mechanism;

Fig. 7 is a schematic illustration of the fluid-pressure jack and clutch-operating mechanism; and

20 Fig. 8 is a side elevation, partly in section, of another valve mechanism associated with the jack-elevating mechanism.

As already stated, the invention is illustrated as embodied in a fastening inserting machine of

25 the type disclosed in the above-identified patent.

The machine disclosed in that patent serves the purpose of inserting fastenings around the heel end of a shoe bottom. In the particular instance, the illustrated machine is adapted to insert fiber fastenings which are severed from a strand of fiber-fastening material and then are successively driven into the work. The work is supported on a jack and is intermittently fed past the operating instrumentalities of the machine.

35 These instrumentalities include an awl (not shown) which is caused to pierce the work and, while remaining in work-piercing position, to feed the work laterally of the machine a predetermined distance. Thereafter the awl is withdrawn from the work, the arrangement being such that the hole made in the work by the awl is now located in register with a fastening inserting driver (not shown). In the meantime a fastening or peg has been severed from the strand

40 of fastening material and has been transferred into the line of drive beneath the driver in readiness to be inserted by the driver into the hole made in the work by the awl. As stated, the work is supported on a jack and the jack is movable to locate the work in operative position in

45 which it is maintained by the clamping pressure of the jack, in readiness for the awl to pierce the work. However, prior to the work-feeding motion of the awl the clamping pressure of the jack is relieved, thus enabling the awl to feed the work.

After completion of a feed step and after the hole made in the work by the awl has been located in register with the driver, the clamping pressure of the jack is restored so that the driver now may insert the fastening into the work while the latter is held firmly clamped in the machine.

The above-outlined sequence of operations is maintained in the illustrated machine and, as pointed out, it is the purpose of the invention primarily to improve upon the jack-operating mechanism, including the mechanism for causing the periodical relief of the clamping pressure of the jack during feed movements of the awl, and the clutch-tripping mechanism which, for its operation, depends upon the jack-operating mechanism.

The machine illustrated in Fig. 1 of the drawings has a frame base 10 carrying a column 12 on which is supported the machine head 14 housing the operating instrumentalities of the machine and their actuating mechanisms. The shoe-supporting jack is indicated at 16 and is of well-known construction. As usual, the jack has a last pin 18 which is adapted to enter the thimble hole of a last on which the shoe to be processed is mounted. A shoe gage 20 of well-known construction is adjustably mounted in the head 14 and determines the distance of the driven fastenings from the edge of the shoe bottom, more specifically, the edge of the heel end portion of the outsole. Moreover, there is secured to the head 14 a work abutment 22, also well-known in the art, against which the shoe is adapted to be clamped by the jack upon elevation of the latter. Rotatably mounted in the head 14 is a cam shaft 24 which carries and is driven by a clutch having the usual driven and driving members 26, 28, the driving member 28 being a pulley. The pulley 28 is driven by a belt 30 connecting it to a pulley directly driven by an electric motor 32.

The illustrated machine is provided with clutch-tripping mechanism for initiating and terminating the rotation of the clutch shaft or cam shaft 24 and, with certain modifications to be presently described, this clutch-tripping mechanism corresponds to the clutch-tripping mechanism disclosed in the above-identified LaChapelle patent. There is mounted on the cam shaft 24 a clutch-controlling spring 34 (Fig. 1) and the hub of the driven clutch member 26 carries a loose ring 36 engaged by a yoke 38 which serves the purpose of throwing out the clutch against the force of the spring 34, the latter tending to throw in the clutch. The yoke 38 is mounted to rock about a fixed stud 40 and its lower end is connected by a toggle 42 to a lever 44 which is pivotally secured at 46 to the head 14. The lever 44 carries at its upper end a cam roll 48 which is in engagement with one end face of a cam block 50 secured on the shaft 24. This end face has a cam portion or rise (not shown) which during each revolution of the cam shaft 24 moves once past the roll 48 and swings the lever 44 in a clockwise direction (as viewed in Fig. 1). The center joint of the toggle 42 is connected by a link 52 to an arm 54 on a shaft 56 rotatable in the head 14. Another arm 58 on the shaft 56 is pivotally secured to a vertical clutch-controlling rod 60. Swinging movement of the arm 58 in clockwise direction (Fig. 1) is limited by engagement of a stop 62 on the arm with the head 14. The rod 60 is guided by a bracket 64 through which the rod extends. A spring 66 on the rod 60 is confined between the bracket 64 and a fixed collar 68 on the rod and tends to depress the rod

60 and to swing the arm 54 in a clockwise direction (as viewed in Fig. 1) to maintain the toggle 42 straight.

The cam portion on the end face of the cam block 50 is so located thereon that the lever 44 is swung in a clockwise direction (as viewed in Fig. 1) toward the end of a machine cycle. If the toggle 42 is straight, this results in rotation of the yoke 38 in a counterclockwise direction (as viewed in Fig. 1) thereby throwing out the clutch against the pressure of the spring 34 and stopping the machine. However, if the toggle 42 is broken, this clockwise swinging movement of the lever 44 is merely an idle motion and the machine operation continues. Thus in the stopping position of the machine the lever 44 is swung out toward the right of Fig. 1, the toggle 42 is straight, and the clutch is disengaged. To initiate a new machine operation the toggle 42 must be broken and this is effected by an upward movement of the clutch-controlling rod 60 against the pressure of its spring 66. As a result of breaking the toggle 42 the spring 34 now is free to trip the clutch, that is to reestablish driving engagement between the two clutch members 26, 28 and initiate the machine operation which will continue indefinitely as long as the toggle 42 is held broken. However, as soon as the rod 60 is permitted to be lowered by the spring 66, the toggle 42 will be straightened again so that the next swinging movement of the lever 44 toward the right of Fig. 1 will again cause the clutch to become disengaged.

As in machines of this type the jack 16 is movable in the heightwise direction of the machine so as to locate the shoe supported thereon in operative clamping position against the abutment 22. The specific construction of the jack is, so far as the present invention is concerned, immaterial and the jack may be of any suitable shape. The jack 16 is supported on a vertically movable rod 70 (Fig. 1) slidably guided in the machine frame. The lower end of the rod 70 is pivotally secured by means of a pin 72 to a two-armed lever 74. The lever 74 is adapted to rock about a horizontal stud 76 which, as will be described, is arranged for vertical movement in the machine. The lower end of the rod 70 is provided with an abutment 78 which is adapted to cooperate with a stop 80. The stop 80 is secured to the machine frame and is vertically adjustable with relation thereto. The stop determines the lowermost position of the rod 70 and, accordingly, of the jack 16. The right-hand end (Fig. 1) of the lever 74 is pivotally connected by a pin 82 to a link 84 which in turn is pivotally secured to a bell crank lever 86. The bell crank lever 86 is mounted for swinging movement on a fixed pin 88 and its horizontal arm is pivotally connected to a link member 90 which is secured to the lower end of a cam-controlled rod 92. As will be noted, the link 84 and the vertical arm of the bell crank lever 86 constitute a toggle which is made or broken by swinging movement of the bell crank lever 86 about its pin 88 under the control of the link 90 and rod 92. The upper end of the rod 92 is pivotally secured to a bell crank lever 94 which is mounted to swing about a fixed pin and the vertical arm of which carries a cam roll 96. The cam roll 96 engages a cam groove 98 cut in the cam block 50 and adapted to impart to the bell crank lever 94 swinging movements during predetermined periods in a machine cycle. The configuration of the cam

groove 98 is such that the toggle 84, 86 is maintained straight in the stopping position of the machine so that elevation of the stud 76 will cause swinging movement of the lever 74 about the pin 82 in a clockwise direction (as viewed in Fig. 1) to elevate the rod 70 and jack 16. This elevation of the jack, as already mentioned, causes the shoe supported thereon to be moved into operative position with relation to the operating instrumentalities of the machine and to be maintained in that position by being clamped against the abutment 22.

It has been mentioned that the work is intermittently fed, there being one feed movement during each cycle of operations. In order to permit the work to be fed, it is of course, necessary temporarily to release its clamping engagement with the abutment 22 by a short downward movement or dip of the jack 16. This dip is effected and controlled by the above-described bell crank lever 94 to which swinging movements are imparted by the cam groove 98. More specifically, immediately prior to the beginning of a work-feeding movement, the bell crank lever 94 is swung in a clockwise direction (as viewed in Fig. 1) to depress the rod 92 and break the toggle 84, 86. Considering for the moment the stud 76 to be vertically immovable, it will be seen that the breaking of the toggle results in a rotation of the lever 74 in a counterclockwise direction (as viewed in Fig. 1) about the stud 76. This rotation in turn causes the jack 16 to move downward sufficiently to relieve the clamping pressure of the shoe against the abutment 22. After the completion of the work-feeding movement, the cam groove 98 causes the bell crank lever 94 to be swung back, that is to be swung in a counterclockwise direction (as viewed in Fig. 1), thereby elevating the rod 92 and again straightening the toggle 84, 86. This causes rotation of the lever 74 in a clockwise direction about the stud 76 and a reelevation of the jack 16 as a result of which the shoe is again clamped against the abutment 22.

The illustrated machine is provided with fluid-pressure actuated mechanism for elevating the jack 16 at the beginning of an operation on the shoe and for initiating the power operation of the machine by the actuation of the above-described clutch-tripping mechanism. The arrangement is such that the jack is elevated with a low pressure sufficient to clamp the shoe against the abutment 22 but insufficient to resist slight adjustments of the shoe with relation to the abutment 22. After locating the shoe in its proper operative position the fluid pressure is increased to produce a final shoe-clamping pressure and simultaneously to operate the clutch-tripping mechanism. To this end the above-mentioned stud 76 is mounted in ears 100 (Figs. 1 and 2) provided on the upper end of a piston rod 102 which with its piston 104 constitutes a ram that is vertically movable in a closed cylinder 106 bolted to the machine base 10. The upper end of the cylinder 106 is closed by a cap 108 having a packed central bore through which the rod 102 slides. Pressure fluid is admitted, as will be described, to the cylinder 106 through a conduit 110 which is in communication with the bottom of the cylinder.

The pressure fluid, such as oil, is contained in a sump casing 112 (Figs. 1, 2 and 7) which is connected by a conduit 114 to a gear pump 116 driven by a belt connecting it to the pulley on

the rotor shaft of the motor 32. The pressure side of the gear pump is indicated at 118.

The pressure side 118 of the pump 116 is in direct communication with a conduit or passage 5 120 (Figs. 4 and 7) which is provided in a valve block 124. The valve block 124 is bolted to the inside of one of the walls of the sump casing 112. In constant communication with the passage 120 is a high pressure regulator 126 of well-known construction. The high pressure regulator 126 is mounted in a vertical bore 128 (Fig. 4) provided in the valve block 124. The lower end portion of the bore 128 which is closed contains a sleeve 130 having diametrically opposite ports 132 so that the pressure fluid may pass from the left-hand portion of the passage 120 (as viewed in Fig. 4) to the right-hand portion of that passage. Slidably mounted in the sleeve 130 is a valve plunger 134 carrying on its upper 10 end a thimble 136 which supports a spring 138 housed in a cup-shaped plunger 140. The plunger 140 is vertically movable in the enlarged upper portion 142 of the bore 128 and abuts with its upper end a set screw 144. The set screw passes 15 through a lid 146 which closes the upper end of the bore 128 and which is secured by screws 148 to the top face of the valve block 124. The screw 144 is held in adjusted position by a locking nut 150. Adjustment of the screw 144 accordingly results in adjustment of the pressure of the spring 138 and thus in adjustment of the pressure at which the regulator 126 will open to permit the pressure fluid to spill over through the regulator. More specifically, when the pressure in the passage 120 exceeds the pressure for which the regulator 126 is set, the valve plunger 134 will be raised so that its upper head opens the upper end of the sleeve 130, permitting the excess pressure fluid to enter the enlarged upper portion 142 of the bore 128 and to flow from there through a conduit 152 back to the sump.

The pressure fluid flows through the conduit 129 to a jack-operating valve 154 (Figs. 4, 5 and 7) also mounted in the valve block 124. The jack-operating valve 154 is arranged for sliding movement in a vertical bore 156 extending from the top to the bottom of the valve block 124. The passage 120 communicates with the bore 156, as illustrated best in Fig. 4 of the drawings. The valve 154 comprises a plunger or stem 158 having lower and upper valve heads 160 and 162. About midway between its upper and lower ends the bore 156 is provided with a port 164 which is in communication with a conduit 166 that leads to a low-pressure regulator or relief valve 168 (Figs. 2 and 7) also of conventional construction, but, as the name already indicates, set to maintain a considerably lower pressure than that maintained by the high-pressure regulator 126. Any fluid which may escape through the low-pressure regulator 168 is conducted back to the sump through a conduit 170 which connects the low-pressure regulator 168 with the sump casing 112 (see Fig. 7).

The above-mentioned jack-operating valve 154 is, as will be described in detail, controlled by the operator, its normal or inoperative position being illustrated in Figs. 4, 5 and 7. The bore 156 in which the valve 154 is movable has near its upper end a port 172 communicating with a conduit 174 which leads back to the sump. As clearly shown in Figs. 4, 5 and 7, in the normal position of the valve 154, the stem 158 and the two heads 160, 162 readily permit the pressure fluid to flow from the conduit 120 through the

middle portion of the bore 156 out of the port 172 into the conduit 174. Accordingly, with the pump 116 in operation the pressure fluid is moved idly in a circuit which includes the sump, the conduit 114, the gear pump 116, the conduit 120, the bore 156, the conduit 174, and again the sump. The pressure of the fluid which is thus delivered by the pump is determined and controlled by the low-pressure regulator 168 which, as described, is in communication through the conduit 166 with the bore 156. The valve heads 160, 162 prevent escape of the pressure fluid into and through the lower and upper portions of the bore 156.

The lower end of the bore 156 which in the normal inoperative position of the valve 154 is cut off by the valve head 160 from the above-defined circuit has a port 176 with which communicates a conduit or passage 178 (Fig. 5). The passage 178 in turn is provided with a port 180 with which communicates a conduit 182 (Figs. 1, 2 and 7). The conduit 182 is in communication with the lower end of a cylinder 184. The cylinder 184 is mounted for limited rocking movement on a pin 186 carried by a bracket 188 secured to the column 12. Vertically movable in the cylinder 184 which is open at its upper end is a clutch-operating piston or ram 190 which is integral with the lower end of the above-described rod 60, upward movement of which causes the tripping of the clutch 26, 28. The upward movement of the piston 190 and the rod 60 is resisted by the spring 66 (as already mentioned) and only when the fluid pressure becomes strong enough to overcome the resistance of the spring 66 will the piston 190 be displaced upwardly in the cylinder 184, thus elevating the rod 60 and throwing in the clutch. The above-mentioned passage 178 (Fig. 5) is in communication with a locking valve 192 located in the valve block 124, and serving to lock the jack against downward movement, as will be described.

Referring specifically to Fig. 5, it will be seen that the valve 192 is located in a bore 194 provided in the valve block 124, the lower end of the bore being closed by a plug 196. Mounted in the bore 194 is a sleeve 198. Movable mounted in the sleeve 198 is a valve plunger 200 having at its lower end a valve head 202 which cooperates with a valve seat formed at the lower extremity 50 of the sleeve 198. The sleeve 198 has at its upper end a flange 204 extending over the top of the valve block 124 and secured thereto by a screw 206. To close the valve 198 the following arrangement is made. The plunger 200 extends a certain distance above the upper end of the flange 204 of the sleeve 198 and is surrounded by a spring 208. The lower end of the spring 208 rests against a washer or plate on the flange 204 and the upper end of the spring abuts a collar 210 secured to the upper end of the plunger 200. It will be noted that the spring 208 tends to elevate the plunger 200 and, therefore, to close the valve 192. The valve 192 is opened by depression of the plunger 200 against the pressure of the spring 208. The sleeve 198 is provided approximately midway between its ends with a port 212 which is in communication with a conduit 214 (Figs. 5 and 7). The conduit 214 leads to a time delay valve 216 which in turn is in communication with the above-described conduit 110 that is connected to the jack-elevating cylinder 106. The construction and operation of the time delay valve will be described later on.

To depress the plunger 200 and open the valve 75

192, the upper end of the plunger 200 is adapted to be engaged by an arm 218 (Figs. 1, 2, 7 and 8) secured on a shaft 220. The shaft 220 is rotatably mounted in a bracket 222 which is bolted to the sump casing 112. Another arm 224 is secured to the shaft 220 and is pivotally connected by a rod 226 to the above-described link 98 which serves to operate the toggle 84, 86. Downward movement of the rod 92 and the link 98 under the control of the cam groove 98 thus not only breaks the toggle 84, 86 but closes the locking valve 192 in causing the arm 218 to swing up, thus permitting the spring 208 to elevate the valve plunger 200.

To enable the operator to move the jack-operating valve 154 so as to cause a movement of the jack into operative position and also to initiate the power operation of the machine, the following mechanism is provided. The upper valve head 162 extends above the valve block 124 and is pivotally connected at 228 (Figs. 4 and 5) to a two-armed lever 230. The lever is mounted to swing about a horizontal pivot 232 (Figs. 4 and 6) which is carried by a bracket 234 secured to the sump casing 112. A link 236 (Fig. 6) connects the lever 230 with a collar 238 clamped on a rod 240. The lower portion of the rod is passed through a bore in a casting 242, the rod being held in fixed relation to the casting 242 by clamping collars 244 and 246. Thus, rod 240 and casting 242 may move as a unit. The lower end of the casting 242 is pivotally secured to a two-armed treadle lever 248 (Fig. 1) mounted to rock about a fixed horizontal pivot stud 250. The outer or forward end of the treadle is engaged by a spring 252 which tends to pull the forward end of the treadle up against snubber or dash pot 254, the purpose of which is to dampen the upward movement of the forward end of the treadle to prevent that end of the treadle from rebounding and initiating another power operation of the machine.

The above-described bracket 188 to which the cylinder 184 is pivotally secured has a downwardly extending portion 256 (Fig. 1) provided with a bore 258 open at its lower end. Received in the bore 258 is the upper end of the rod 240, the movements of which are thereby guided. The rod 240 carries a spring 260 which is confined between an upper collar 262 slidable on the rod 240 and a lower clamping collar 264 fixed on the rod 240. Accordingly, on elevation of the rod 240 the collar 262 is ultimately brought into engagement with the portion 256 of the bracket 188 with the result that the spring 260 becomes compressed and offers resistance to the continued upward movement of the rod 240. The purpose of this arrangement will be described in connection with the description of the machine operation.

The above-mentioned time delay valve 216 comprises a casing 266 (Fig. 7) with the interior of which is connected the already-mentioned conduit 214. Before the conduit 214 enters the casing it has a branch conduit 268 leading to a different portion of the casing, as will be described. The pressure fluid entering the casing through the conduit 214 encounters a ball valve 270 which is opened to permit the fluid to pass unimpeded through the delay valve into the conduit 110. Provided in the casing 266 is a chamber 272 in which is movable a spring-biased hollow plunger 274. The chamber 272 is provided with an annular groove 276 which establishes direct communication between the passage of the ball valve 270 and the conduit 110 so that the pressure fluid

entering through conduit 214 can always flow unimpeded to the conduit 110 and the cylinder 106 to elevate the jack-operating piston 104 without delay. The already-mentioned branch conduit 268 is in communication with a conduit containing a ball valve 278 which is opened by the fluid under pressure which thus is conducted into the right-hand end portion of the chamber 272 where it immediately acts against the right-hand end face of the plunger 274 to overcome the light resistance of its biasing spring. The result of this is a rapid displacement of the plunger 274 toward the left of Fig. 7 against the pressure of its spring so that the right-hand end of the plunger 274 is displaced sufficiently toward the left of Fig. 7 to establish communication between the lower end of the conduit 110 and the right-hand end portion of the chamber 272. This condition obtains while the cylinder 106 is under pressure, the piston 104 is up and the jack in its elevated operative position. If now the passage 178 is cut off from the source of pressure fluid by the elevation of the treadle 248 and the raising of the valve 154 into its normal inoperative positive (shown in Figs. 4 and 5) the fluid contained in the cylinder 106 and the conduit 110 cannot immediately escape back to the passage 178 but is by-passed through the above-mentioned communication between the lower end of the conduit 110 and the right-hand end portion of the chamber 272 through a needle valve 280 arranged in a passage which is in communication with the branch conduit 268. The lowering of the piston 104 and the jack 16 is thus delayed until after the pressure of the fluid trapped in the cylinder 106 and conduit 110 has been reduced sufficiently through the leakage of the pressure fluid past the needle valve 280 to permit the plunger 274 to be returned toward its right-hand position by its spring. As soon as an annular recess 282 provided in the periphery of the plunger 274 is in communication with the lower end of the conduit 110; the excess pressure fluid in the cylinder 106 and conduit 110 is quickly exhausted via the annular recess 282 which is in direct communication with the conduit 214. The pressure fluid flowing back through the conduits 268 and 214 and the open locking valve 192 is drained out through the passage 178 and the lower end of the bore 156 back into the sump. The setting of the needle valve 280 determines the time delay in the lowering of the jack.

The purpose of the provision of the time delay valve 216 is to insure that on stopping the machine operation the last fastening is securely driven into the work. It may occur that the operator in releasing the treadle 248 to cut off the passage 178 and conduit 182 from the source of pressure fluid will inadvertently delay this action somewhat by not taking his foot off the treadle quickly enough with the result that the cam portion on the end face of the cam block 50 will move past the cam roll 48 and thus permit the initiation of another cycle of operations even though the valve 154 has been raised to cut off the passage 178 and the conduit 182 from the supply of pressure fluid and to initiate the exhaust of excess pressure fluid from the passage 178 and the conduit 182. Accordingly, if no time delay valve were provided between the passage 178 and the jack-operating cylinder 106, the jack would descend immediately and the last fastening produced as the result of the additional cycle of operation above-mentioned would be incompletely driven into the shoe since the latter would

be already descending with the jack. It will be noted that the lowering of the piston 104 and jack 16 is delayed only initially and that after an adjustable lapse of time the cylinder 106 and conduit 110 may be exhausted quickly without any impeding action on the part of the time delay valve 216.

To lock the jack 16 against undesired further upward movement at a certain time during a cycle of operations the following hydraulic locking mechanism has been provided. Mounted on the sump casing 112 is a valve casing 284 (Figs. 1, 2, 7 and 8) which contains an oil reservoir 286. The oil reservoir 286 is in communication by means of a port and passage 288 with a bore 290 (Fig. 8) in which is vertically movable a valve plunger 292. The lower portion of the valve plunger 292 is of reduced diameter and carries at its lower extremity a valve head 294 which cooperates with a valve seat formed by a shouldered portion of the bore 290. A spring 296 tends to raise the plunger 292 and press the valve head 294 against its seat to close the valve. The upper end of the spring engages the valve head 294 and the lower end of the spring is seated in an axial bore provided in a cap screw 298 which closes the lower end of the bore 290. The passage 288 is in communication with the bore 290 above the valve head 294. Below the valve head 294 the bore 290 is in communication with a conduit 300 which leads to the upper portion of the cylinder 106. The reservoir 286 being filled with oil and being open to the atmosphere, it will be understood that with the valve 292 open the downward movement of the piston 104 sucks oil from the reservoir 286 through the open valve 292 and conduit 300 into the upper portion of the cylinder 106 above the piston 104. Reversely, upward movement of the piston 104 displaces oil from the upper portion of the cylinder 106 through the conduit 300 and open valve 292 back into the reservoir 286. However, it will also be understood that if the valve 292 is closed no such oil can be displaced from the upper portion of the cylinder 106, thus locking the piston 104 against upward movement.

To open the valve 292 against the pressure of the spring 296 the following mechanism is provided. The abovementioned shaft 220 to which is secured the arm 218 operating the valve 192 also has secured to it an arm 302 (Fig. 8), the free end of which is pivotally connected by a link 304 to a two-armed lever 306 adapted to rock about a pivot pin 308 carried in a bracket 310 secured to the valve casing 284. The left-hand arm (as seen in Fig. 8) of the lever 306 is in engagement with the upper end of the valve plunger 292 which projects beyond the valve casing 284. It will be noted that rotation of the shaft 220, as above described, to permit the closing of the valve 192 by its spring 208 will rotate the lever 306 in a clockwise direction (as viewed in Fig. 8), thus simultaneously permitting the spring 296 to close the valve 292. Accordingly, the piston 104 is simultaneously locked against downward and upward movement by the respective valves 192 and 292.

The machine operation is substantially as follows: After a lasted shoe has been placed upon the last pin 18 of the jack 16 and after the motor 32 has been started, thereby causing the pump 116 to operate and to circulate the pressure fluid idly in the above-described circuit 112, 114, 116, 118, 120, 156, 166, 174, and back to the sump 112 the operator steps on the treadle 248 and causes

the upward movement of the casting 242 and rod 240 (Figs. 1 and 6) as a result of which the lever 230 is swung in a clockwise direction (as viewed in Fig. 7) to depress the valve 154. It is only after a relatively short downward movement of the valve plunger 158 and heads 160, 162 that the lower head 160 of the valve opens the port 176 to establish communication with the passage 120 in which there is fluid under pressure and at the same time the upper head 162 closes the port 172, thus preventing further escape of the pressure fluid back to the sump through pipe 174. In stepping on the treadle 248 the operator depresses it only until he feels the resistance of the spring 260 at which time the port 176 leading to passage 178 has been fully opened so that the pressure fluid can enter through the then open locking valve 192, conduit 214, delay valve 216, and conduit 110 into the jack-operating cylinder 106, thus causing the elevation of the piston 104 and, accordingly, the elevation of the jack 16 to clamp the shoe against the abutment 22.

The elevation of the jack is accomplished briefly as follows. It has been mentioned that in the inoperative position of the machine the toggle 84, 86 is straight and is positively maintained in that position. With the toggle being held straight, the locking valves 192 and 292 are simultaneously held open as the result of the connection of the valve-operating arms 218 and 302 with the toggle-operating link 90. Elevation of the jack-operating piston 104 causes elevation of the stud 76 and swinging movement of the lever 74 in a clockwise direction (as viewed in Fig. 1) about the pivot 82, thereby elevating the jack 16 as described. As already mentioned, this is effected under low pressure since the bore 156 is still connected by the conduit 163 to the low-pressure regulator 168.

With the opening of the port 176 to the pressure fluid, by virtue of the head 160 now being below port 176, the port 180 (Fig. 5) is also opened so that the pressure fluid also can flow through conduit 182 and act on the clutch-operating piston 190. However, the spring 66 which opposes the upward movement of the clutch-operating piston 190 under the action of the pressure fluid is sufficiently strong to prevent such upward movement after the conduit 182 has been opened to the pressure fluid so long as the pressure of the fluid in the conduit 120 and bore 156 is controlled by the low-pressure regulator 168.

The shoe having been clamped against the abutment 22 under the action of the low-pressure fluid against the jack-operating piston 104, it is still possible to make adjustments of the work with relation to the abutment 22 and edge gage 20.

After the final position of the work in the machine is deemed satisfactory the operator fully depresses the treadle 248, thereby causing further downward movement of the operating valve 154 with the result that the upper valve head 162 closes the port 164 and disconnects the conduit 166 from the bore 156. Since the low-pressure regulator 168 is now cut off from the supply of pressure fluid, the pressure of the fluid is now controlled only by the high-pressure regulator 126 which, as previously described, is continuously in communication with the passage 120. The result is an increase of the pressure of the fluid in the passage 120, the bore 156 and the conduits 178 and 182 so that the jack-operating piston 104 is now maintained in its uppermost position under the full pressure of the fluid,

thus causing the shoe to be clamped with full pressure against the abutment 22. Moreover, the increase of the pressure of the fluid in the conduit 182 is sufficient to overcome the resistance of the spring 66 to the upward movement of the clutch-operating piston 190. Thus the piston 190 is thrust upward to break the toggle 42 and permit the spring 34 to move the clutch member 26 into engagement with the clutch member 28. This initiates the power rotation of the cam shaft 24, and the operation of the instrumentalities of the machine which are controlled by the cam shaft 24. It will thus be noted also, that the power operation of the machine cannot be started, unless and until the jack is up in its operative position.

It has been mentioned that at the beginning of a machine cycle the awl is caused to pierce the work whereupon the awl is caused to move laterally of the machine to feed the work. Prior to the work-feeding movement of the awl the cam groove 98 imparts a swinging movement to the bell crank lever 94 in a clockwise direction (as viewed in Fig. 1) as a result of which the rod 92 is depressed. The depression of the rod 92 results in three things, namely, the toggle 84, 86 is broken, the arm 224 is swung in a counterclockwise direction (as viewed in Fig. 1) to permit the closing of the locking valve 192 by the spring 208, and the arm 302 is swung in a counterclockwise direction (Fig. 8) to permit the closing of the locking valve 292 by the spring 296.

The closing of the valve 192 results in locking the piston 104 against downward movement since the pressure fluid in the cylinder 106, the conduits 110, 214, and the delay valve 216 cannot escape back into the conduit 178. Thus the stud 76 becomes a fixed pivot for the lever 74. The breaking of the toggle 84, 86 results in a short rocking movement of the lever 74 in a counterclockwise direction (as viewed in Fig. 1) about the stud 76 and this in turn causes a brief downward movement or dip of the jack 16 sufficient to relieve the clamping pressure of the shoe against the abutment 22 to permit the shoe to be fed by the awl.

As just described, the brief downward movement or dip of the jack 16 during the work-feeding operation of the awl is caused by a breaking of the toggle 84, 86 which results in a rocking movement of the lever 74 in a counterclockwise direction (as viewed in Fig. 1). It has been observed, however, that since the breaking of the toggle 84, 86 is apt to occur much faster than the downward movement of the jack 16, the lever 74 is apt not to rock about the stud 76 as it should but to swing in a counterclockwise direction (as viewed in Fig. 1) about the pin 72. This would elevate the jack-operating piston 104 and possibly interfere with the proper feed motion of the work, were it not for the provision of the additional locking valve 292 (Figs. 7 and 8) which prevents such upward movement of the piston 104 at the time the jack 16 receives its brief downward movement or dip during the work-feeding operation.

As previously explained, the valve 292 is operated simultaneously with the locking valve 192 by connections to the same shaft 220, there being oil at opposite sides of the piston 104 which at the feed interval becomes locked by the respective valves 192 and 292, thus effectively preventing the downward, as well as the upward, movement of the piston 104 and, accordingly, estab-

lishing the stud 76 as a truly fixed pivot for the lever 74 during the downward movement or dip of the jack.

After the completion of a work-feeding movement the cam groove 98 causes a reverse swinging movement of the bell crank lever 94 in a counterclockwise direction (as viewed in Fig. 1) to elevate the rod 92. The elevation of the rod 92 again opens the locking valves 192, 292 so that the full hydraulic pressure again can act on the jack-operating piston 104 to elevate the jack. The elevation of the rod 92 also causes the toggle 84, 86 to be straightened. The timing is such that the toggle is straightened before the locking valves 192, 292 become opened so that the straightening of the toggle takes place while the stud 76 is still held fixed in the machine. Thus on straightening of the toggle 84, 86 the lever 74 is swung in a clockwise direction (as viewed in Fig. 1) about the stud 76 to reelevate the jack and to restore the clamping pressure of the shoe against the abutment 22.

The machine cycle will be repeated indefinitely as long as the treadle is maintained depressed. On release of the treadle the valve 154 is again raised to its normal inoperative position in which the pressure fluid may circulate idly in the fluid pressure mechanism, the clutch-operating cylinder 184 and the jack-operating cylinder 196 becoming cut off from the supply of pressure fluid by the upward movement of the lower head 160 of the valve 154. Excess fluid in the conduits 178 and 182 spills out through a drain passage, which actually is the lower end of the bore 156, back into the sump casing 112. The piston 104 is brought back to its initial lowermost position under the weight of the parts supported by it and the clutch-operating piston 190 is lowered by the spring 66. Lowering of the piston 104 causes a lowering of the jack 16 into its inoperative position. Lowering of the clutch-operating piston 190 causes the toggle 42 to become straightened and the clutch member 28 to be disengaged from the clutch member 28 by the cam portion on the end face of the cam block 50 acting on the cam roll 48. All machine parts having been returned into their initial positions, the machine is now ready for the initiation of the operation upon the next shoe to be processed.

Having thus described my invention, what I claim as new and desire to secure by Letters Patent of the United States is:

1. In a shoe machine, a movable shoe-supporting jack adapted to locate a shoe in operative position in the machine, fluid-pressure mechanism for moving the jack, a fluid-pressure circuit including a pressure generating source, a valve for establishing communication between said mechanism and said circuit, and pressure selective means associated with the valve for causing an increase of the pressure of the fluid in said circuit after the jack has located the shoe in operative position.

2. In a shoe machine, a movable shoe-supporting jack adapted to locate a shoe in operative position in the machine, fluid-pressure mechanism for moving the jack, a fluid-pressure circuit including a pressure generating source, an operator-controlled valve member for establishing communication between said mechanism and said circuit, and a pressure selective member associated with the valve member for causing an increase of the pressure of the fluid in said circuit after the jack has been moved by said mechanism.

3. In a shoe machine, a clutch shaft, clutch-tripping mechanism for causing rotation of the shaft, a movable shoe-supporting jack adapted to locate a shoe in operative position in the machine, fluid-pressure mechanism for moving the jack, a fluid-pressure circuit including a pressure generating source, means for connecting said mechanism with said circuit, selective means associated with the connecting means for causing an increase of the pressure of the fluid in said circuit after the jack has located the shoe in operative position, and fluid-pressure means adapted upon increase of the pressure of the fluid in said circuit to operate the clutch-tripping mechanism.

4. In a shoe machine, a clutch shaft, clutch-tripping mechanism for causing rotation of the shaft, a movable shoe-supporting jack adapted to locate a shoe in operative position in the machine, fluid-pressure mechanism for moving the jack, a fluid-pressure circuit including a pressure generating source, an operator-controlled valve member for establishing communication between said mechanism and said circuit, a pressure selective member movable with the valve member for causing an increase of the pressure of the fluid in said circuit after the jack has been moved to locate the shoe in operative position, and a fluid-pressure ram adapted upon increase of the pressure of the fluid in said circuit to operate the clutch-tripping mechanism.

5. In a shoe machine, a clutch shaft, clutch-tripping mechanism for causing rotation of the shaft, a movable shoe-supporting jack adapted to locate a shoe in operative position in the machine, fluid-pressure mechanism for moving the jack, a fluid-pressure circuit including a pressure generating source, an operator-controlled valve member for establishing communication between said mechanism and said circuit, a pressure selective member movable with the valve member for causing an increase of the pressure of the fluid in said circuit after the jack has been moved to locate the shoe in operative position, a fluid-pressure ram connected to said circuit and adapted to operate the clutch-tripping mechanism, and a spring tending to maintain the ram inoperative, the spring being adapted to yield upon increase of the pressure of the fluid in the circuit to permit the operation of the ram.

6. In a shoe machine, a movable shoe-supporting jack adapted to locate a shoe in operative position in the machine, fluid-pressure mechanism for moving the jack, a fluid-pressure circuit including a low-pressure regulator and a high-pressure regulator, means for connecting said mechanism with said circuit, and means associated with the connecting means for cutting off the low-pressure regulator from the circuit after the jack has located the shoe in operative position.

7. In a shoe machine, a clutch shaft, clutch-tripping mechanism for causing rotation of the shaft, a movable shoe-supporting jack adapted to locate a shoe in operative position in the machine, fluid-pressure mechanism for moving the jack, a fluid-pressure circuit including a low-pressure regulator and a high-pressure regulator, an operator-controlled valve member for establishing communication between said mechanism and said circuit, a pressure selective member integral with the valve member for cutting off the low-pressure regulator from the circuit after the jack has been moved to locate the shoe in

operative position, and a fluid-pressure ram adapted after cutting off the low-pressure regulator from the circuit to operate the clutch-tripping mechanism.

8. In a shoe machine, a clutch shaft, clutch-tripping mechanism for causing rotation of the shaft, a movable shoe-supporting jack adapted to locate a shoe in operative position in the machine, fluid-pressure mechanism for moving the jack, a fluid-pressure circuit including a low-pressure regulator and a high-pressure regulator, an operator-controlled valve member for establishing communication between said mechanism and said circuit, a pressure selective member integral with the valve member for cutting off the low-pressure regulator from the circuit after the jack has been moved to locate the shoe in operative position thereby increasing the fluid pressure of the circuit, a fluid-pressure ram connected to said circuit and adapted to operate the clutch-tripping mechanism, and a spring tending to maintain the ram inoperative, the spring being adapted to yield upon increase of the fluid pressure of the circuit to permit the operation of the ram.

9. In a shoe machine, a work abutment, a shoe-supporting jack adapted to elevate and clamp a shoe against the abutment, a source of hydraulic pressure, hydraulic jack-elevating mechanism, a low-pressure hydraulic circuit, an operator-controlled valve member for establishing hydraulic communication between said mechanism and said circuit, and pressure selective means associated with said valve member for causing an increase of the pressure of the fluid in the circuit after the jack has been elevated to clamp the shoe against the abutment.

10. In a shoe machine, a clutch shaft, clutch-tripping mechanism for causing rotation of the shaft, a work abutment, a shoe-supporting jack adapted to elevate and clamp a shoe against the abutment, hydraulic jack-elevating mechanism, a low-pressure hydraulic circuit, an operator-controlled valve member for establishing hydraulic communication between the jack-elevating mechanism and the hydraulic circuit, means associated with said valve member for causing an increase of the pressure of the fluid in the circuit after the jack has been elevated to clamp the shoe against the abutment, and a hydraulically operated mechanism adapted upon increase of the pressure of the fluid in the circuit to operate the clutch-tripping mechanism.

11. In a shoe machine, a clutch shaft, clutch-tripping mechanism for causing rotation of the shaft, a work abutment, a shoe-supporting jack adapted to elevate and clamp a shoe against the abutment, a source of hydraulic pressure, hydraulic jack-elevating mechanism, a low-pressure hydraulic circuit, an operator-controlled valve member for establishing hydraulic communication between the jack-elevating mechanism and the hydraulic circuit, pressure selective means associated with said valve member for causing an increase of the pressure of the fluid in the circuit after the jack has been elevated to clamp the shoe against the abutment, a hydraulically operated mechanism connected to said circuit and adapted to operate the clutch-tripping mechanism, and a spring tending to maintain the last-mentioned hydraulically operated mechanism inoperative, the spring being adapted to yield upon increase of the pressure of the fluid in the circuit to permit the operation of said hydraulically operated mechanism.

12. In a shoe machine, a work abutment, a shoe-supporting jack adapted to elevate and clamp a shoe against the abutment, a hydraulic ram for elevating the jack, a hydraulic circuit including a low-pressure regulator and a high-pressure regulator, an operator-controlled valve member adapted to establish communication between the hydraulic ram and the hydraulic circuit, and a pressure selective member movable with the valve member and adapted to cut off the low-pressure regulator from the circuit after the elevation of the jack.

13. In a shoe machine, a clutch shaft, clutch-tripping mechanism for causing rotation of the shaft, a work abutment, a shoe-supporting jack adapted to elevate and clamp a shoe against the abutment, a hydraulic ram for elevating the jack, a hydraulic circuit including a low-pressure regulator and a high-pressure regulator, an operator-controlled valve member adapted to establish communication between the hydraulic ram and the hydraulic circuit, a pressure selective member movable with the valve member and adapted to cut off the low-pressure regulator from the circuit after the elevation of the jack so as to cause an increase of the pressure of the fluid in the hydraulic circuit, and another hydraulic ram adapted upon increase of the pressure of the fluid in the circuit to operate the clutch-tripping mechanism.

14. In a shoe machine, a clutch shaft, clutch-tripping mechanism for causing rotation of the shaft, a work abutment, a shoe-supporting jack adapted to elevate and clamp a shoe against the abutment, a hydraulic ram for elevating the jack, a hydraulic circuit including a low-pressure regulator and a high-pressure regulator, an operator-controlled valve member adapted to establish communication between the hydraulic ram and the hydraulic circuit, another valve member movable with the first-mentioned valve member and adapted to cut off the low-pressure regulator from the circuit after the elevation of the jack so as to cause an increase of the pressure of the fluid in the hydraulic circuit, another hydraulic ram connected to said circuit and adapted to operate the clutch-tripping mechanism, and a spring tending to maintain the last-mentioned ram inoperative, the spring being adapted to yield upon increase of the fluid pressure of the circuit to permit the operation of said last-mentioned ram.

15. In a shoe machine, a movable shoe-supporting jack adapted to locate a shoe in operative position in the machine, a power-operated cam shaft, a cam on the cam shaft, fluid pressure jack-operating mechanism, a fluid-pressure circuit including a pressure generating source, means for connecting the jack-operating mechanism with the fluid-pressure circuit, pressure selective means associated with the connecting means for causing an increase of the fluid pressure of the circuit after the jack has located the shoe in operative position, means for locking the jack-operating mechanism in operative position, and means under the control of said cam for releasing the locking means at a predetermined point in each machine cycle.

16. In a shoe machine, a movable shoe-supporting jack adapted to locate a shoe in operative position in the machine, a power-operated cam shaft, a cam on the cam shaft, hydraulic jack-operating mechanism, a source of hydraulic pressure, a low-pressure hydraulic circuit, an op-

17

erator-controlled valve member for hydraulically connecting the jack-operating mechanism with said circuits, a pressure selective member integral with the valve member for causing an increase of the fluid pressure of the circuit after the jack has located the shoe in operative position, means for hydraulically locking the jack-operating mechanism in operative position, and means under the control of said cam for releasing the locking means at a predetermined point in each machine cycle.

17. In a shoe machine, a clutch-controlled cam shaft, clutch-tripping mechanism for causing rotation of the shaft, a cam on the shaft, a movable shoe-supporting jack adapted to locate a shoe in operative position in the machine, hydraulic jack-operating mechanism, a source of hydraulic pressure, a low-pressure hydraulic circuit, a valve member for establishing communication between the jack-operating mechanism and said circuit, a pressure selective member movable with the valve member for causing an increase of the fluid pressure of said circuit after the jack has been moved to locate the shoe in operative position in the machine, means for hydraulically locking the jack-operating mechanism, hydraulic means for operating the clutch-tripping mechanism upon increase of the fluid pressure of the hydraulic circuit, and means under the control of said cam for releasing the locking means at a predetermined point in each machine cycle.

18. In a shoe machine, a clutch-controlled cam shaft, clutch-tripping mechanism for causing rotation of the shaft, a cam on the shaft, a movable shoe-supporting jack adapted to locate a shoe in operative position in the machine, a cylinder, a piston movable in the cylinder to move the jack, a hydraulic circuit including a low-pressure regulator and a high-pressure regulator, an operator-controlled valve member for admitting pressure fluid from said circuit to said piston to operate the jack, a pressure selective member integral with the valve member and adapted to cut off the low-pressure regulator from the circuit so as to increase the fluid pressure of the circuit after the jack has been moved to locate the shoe in operative position in the machine, hydraulic means for operating the clutch-tripping mechanism upon increase of the fluid pressure of the circuit, a spring-biased valve for severing the hydraulic connection between the cylinder and the circuit to lock the piston and jack in operative position, and means under the control of said cam for opening the last-mentioned valve to release the jack at a predetermined point in each machine cycle.

19. In a shoe machine, a movable shoe-supporting jack adapted to locate a shoe in operative position in the machine, a power-operated cam shaft, a cam on the cam shaft, fluid-pressure jack-elevating mechanism, a source of fluid under pressure, means for connecting the jack-elevating mechanism with the source of fluid under pressure, means associated with the connecting means for increasing the fluid pressure of the circuit after the jack has located the shoe in operative position, means for locking the jack-elevating mechanism in operative position, and means under the control of the cam for periodically rendering the locking means operative and causing a downward movement of the jack.

20. In a shoe machine, a cam shaft, a clutch on the shaft, clutch-tripping mechanism, a movable shoe-supporting jack adapted to locate a shoe in operative position in the machine, a hydraulic

18

circuit, hydraulic jack-elevating mechanism, a valve for establishing communication between the circuit and the jack-elevating mechanism, an operator-controlled member for actuating the valve, a spring active after the elevation of the jack to resist further actuation of the valve, means associated with the valve and active as a result of continued movement of the operator-controlled member against the resistance of the spring to increase the fluid pressure of the circuit, and means active as a result of the increase of the fluid pressure to operate the clutch-tripping mechanism.

21. In a shoe machine, a movable shoe-supporting jack adapted to locate a shoe in operative position in the machine, fluid-pressure mechanism for moving the jack, a fluid-pressure circuit, a conduit between the circuit and the fluid-pressure mechanism, an operator-controlled valve in said conduit for establishing communication between said mechanism and said circuit, another valve in said conduit and designed to retard the flow of fluid from the fluid-pressure mechanism.

22. In a shoe machine, a vertically reciprocating shoe-supporting jack adapted to elevate a shoe into operative position in the machine, fluid-pressure mechanism for elevating the jack, a supply of fluid under pressure, a conduit between the supply and the elevating mechanism, an operator-controlled valve in said conduit for establishing communication between the supply and the elevating mechanism, another valve in said conduit and designed to retard the drainage of pressure fluid from the elevating mechanism.

23. In a shoe machine, a clutch shaft, clutch-tripping mechanism for causing rotation of the shaft, a vertically reciprocating shoe-supporting jack adapted to locate a shoe in operative position in the machine, a hydraulically operated ram for elevating the jack, a hydraulic circuit, a conduit between the circuit and the ram, an operator-controlled valve in the circuit for establishing communication between the circuit and the ram, another valve in the conduit designed to retard the return of pressure fluid from the ram, means associated with the first-mentioned valve for increasing the fluid pressure of the hydraulic circuit after the jack has located the shoe in operative position, and fluid-pressure means adapted upon increase of the fluid pressure of the circuit to operate the clutch-tripping mechanism.

24. In a shoe machine, a movable shoe-supporting jack adapted to locate a shoe in operative position in the machine, a power-operated cam shaft, a cam on the cam shaft, fluid-pressure jack-operating mechanism, a fluid-pressure circuit, means for connecting the jack-operating mechanism with the fluid-pressure circuit, means associated with the connecting means for increasing the fluid pressure of the circuit after the jack has located the shoe in operative position, valve means for locking the jack-operating mechanism in operative position against movement in opposite directions, and means under the control of said cam for releasing the locking means at a predetermined point in each machine cycle.

25. In a shoe machine, a clutch-controlled cam shaft, clutch-tripping mechanism for causing rotation of the shaft, a cam on the shaft, a movable shoe-supporting jack adapted to locate a shoe in operative position in the machine, a cylinder, a piston movable in the cylinder to move the jack, a hydraulic circuit including a low-pressure regulator and a high-pressure regulator, an operator-controlled valve member for admitting

pressure fluid from said circuit to said piston to operate the jack, a pressure selective member integral with the valve member and adapted to cut off the low-pressure regulator from the circuit so as to increase the fluid pressure of the circuit after the jack has been moved to locate the shoe in operative position in the machine, hydraulic means for operating the clutch-tripping mechanism upon increase of the fluid pressure of the circuit, spring-biased valves for locking the piston and jack in operative position against upward as well as downward movement, and means under

5

10

the control of said cam for opening the said spring-biased valves to release the jack at a predetermined point in each machine cycle.
